FLUID METER

Horace Chrisman, Edgewood, and George J. Gengung, Wilkinsburg, Pa., assignors to Pittsburgh Equitable Meter Company, Pittsburgh, Pa., a corporation of Pennsylvania

Application November 9, 1939, Serial No. 303,634

5 Claims. (Cl. 73—246)

The present invention relates to meters intended primarily for measuring very small flows, such as the gasoline consumed in operating a gasoline motor propelled automobile.

It is an object of the invention to provide a meter which is small and compact and which is responsive to very small flows.

Another object is the provision of a meter which is of simple construction, is of light weight and is relatively inexpensive to manufacture.

A further object is the provision of a meter having a relatively small overall pressure loss.

These and other objects of the invention will be apparent from a consideration of the following specification, taken in connection with the accompanying drawing, wherein I have shown a preferred embodiment of the invention by way of example, and wherein:

Figure 1 is a vertical section through the center of the meter.

Figure 2 is a bottom elevation of the meter with the bottom cover and bottom piston heads removed.

Figure 3 is a section taken through a cylinder and piston on line III—III of Figure 1.

Figure 4 is an enlarged side view of a piston with certain parts in section.

Figure 5 is a section of the casing taken on the line V—V of Figure 2, the valve and crank-shaft being removed.

Figure 6 is an elevation of a detail of the piston.

Figure 7 is a side elevation of the valve member.

Figure 8 is a side elevation of the valve driver member, and

Figure 9 is a side elevation of the valve spring.

Referring to the drawing, there is shown a casing 1 having cylinders 2 and 3 bored therethrough and providing partitions or walls 4 and 5 separating the cylinders from a valve or distributing chamber 6. Liners 7 and 8 of brass or other suitable material are pressed into the cylinders to provide a wearing surface therefor, if desired. Preferably the casing is made of aluminum or an aluminum alloy in order to eliminate as much weight as possible, but any other suitable material may be employed, and, if desired, the case may be formed in two parts on the section line V—V of Figure 2 and suitably secured together. A top cover 9 is provided, having a boss 10 which is bored and threaded at 11 to provide an inlet to the meter communicating with a middle recess 12 in the wall 4 opening into the distribution chamber 6. Two distribution passages 13 and 14 (Figure 5) are provided in the upper half of the wall 4. Passage 14 connects with port 15

in the cover which extends around boss 10 and merges with the distributing head chamber 16 in the cover for cylinder 3. Passage 13 connects with the distributing head chamber 17 for cylinder 2. A middle exhaust passage 19 provided in wall 4 communicates with bore 20 in the boss 21 in the bottom cover, which serves as the outlet for the meter, and distribution passages 22 and 23 in the lower half of wall 4 connect respectively with distributing head chamber 25 for cylinder 3 and distributing head chamber 26 for cylinder 2. A central bore 28, which serves as an exhaust port, connects with passage 19. The four cored ports 31, 32, 33 and 34 formed in the face of wall 4 surrounding bore 28, separated by ribs 35, 36, 37 and 38, merge with the passages 13, 14, 22 and 23 respectively, and the face of wall 4 is recessed at 39 to receive a valve seat member 40 with ports and ribs in communication with those of the casing.

The casing is bored transversely through the walls 4 and 5 and flanged bushings 42 and 43 are inserted in these bores with a pressed fit. A crankshaft 44 is journalled in the bushings and has secured thereto a worm 45 located in exhaust passage 19 for driving the register, as will hereafter appear. A bore 46 normally closed by a plug 47 is provided in the outer wall to enable the drilling of the holes in the inner walls and insertion of the bushings and crankshaft. At each end crankshaft 44 carries a crank arm 48 secured thereto by a tapered pin 50 threaded into the crank arm and extending through a transverse bore in the crankshaft. Crank arms 48 are arranged 90° from each other and preferably are shaped with a mass 49 near the shaft to counterbalance the moment of the crank arm. A crank pin 51 extends through a suitable bore in the crank arm and is held in place by a cotter pin 52 or by any other suitable means. Pins 51 carry a roller 53 thereon having a circumferential groove 54 in its periphery. Crank arm 48 at the other end of the shaft carries a roller 53 in a similar manner.

There are two double acting pistons 60 and 61 mounted to reciprocate in the cylinders 2 and 3 respectively, and as these pistons are alike in construction, only one will be described in detail. The piston 61 comprises a pair of spacer members 62 and 63, preferably made of sheet metal turned over at their ends as indicated at 64, 65 and having the piston head assemblies 66 and 67 secured thereto. Piston head assembly 66 comprises a bottom plate 68 having a cupped washer 70 of leather or other suitable material

thereon, a top backing plate 71, and a third plate 74 having a plurality of offset tabs 72 which hold an endless coil spring 73 in position to resiliently expand the leather washer into engagement with the wall of the cylinder. A plurality of rivets 75 holds the plate 68, washer 70 and top plate 71 assembled, and the piston head 66 is held assembled to the spacers 62, 63 by the screws 76. Piston 61 has similar heads 77 and 78 held in assembled relation to similar spacers 81 and 82.

Piston 61 has two spaced bars 84 and 85 extending through suitable holes in the sides of spacers 62 and 63, said bars having circumferential grooves at their outer ends, as indicated at 86 (Figure 6). In assembled position a bent spring wire retainer 87 received in grooves 86 at each end retains the bars against endwise movement. The bars receive the rollers 54 and 58 on crank pins 51 therebetween and are so disposed as to provide a slight clearance therewith so that the rollers may freely roll between the bars. If desired, sufficient clearance may be provided for adjusting the accuracy of the meter. The laterally bent portions of spacers 62, 63 and 81, 82 engage the bushings 43 and 42 respectively and serve to guide the piston against oscillating or turning movement in its reciprocation.

A valve member 85' is journalled loosely on the crankshaft 44 and comprises a plate 86' having a supply port 87' and an integral housing 90 covering an exhaust port 91. Supply passage 87' extends circumferentially for slightly less than 90°, or which is sufficient to expose a port 33 and part of two ribs 35 and 36. The exhaust port 91 also extends circumferentially for slightly less than 90°. A driving member 92 is rigidly secured on the crankshaft by a set screw or in any other suitable manner, and comprises bosses 93 and 94 spaced apart to receive the bar 96 extending from the top of the valve member. Set screws 97 and 98 threaded through the bosses engage bar 96 and provide an adjustable driving connection between the crankshaft and valve whereby the timing of the valve may be accurately adjusted. A dished star shaped spring 101 is provided between the valve and driver to co-operate with the inlet pressure to maintain the valve on its seat. A weight or mass 102 secured to the driver 92 is selected and adjusted to co-operate with the weights 49 to substantially balance the moment of the pistons and valve so as to cause smooth operation of the meter. However, on operating the meter with the pistons reciprocating horizontally, this counter-balance may be omitted, if desired.

The casing is transversely bored at 105 to receive a bushing 106 extending through the exhaust passageway 19 and supply passage 23, said bushing being threaded at its outer end. A shaft 107, journalled in the bushing, carries a worm wheel 108 at its inner end which meshes with the worm 45 on the crankshaft, the outer end of this shaft passing through a stuffing box 110 formed by a gland threaded on the end of bushing 106 and carrying a worm 111. A plate 112 is secured to the casing by means of screws 113 and spacers 114 and a bracket 115 is secured to the plate and is bored to receive a shaft carrying a worm wheel 118 at one end and a pinion 120 at the other end meshing with a gear 119. A counter 121 is suitably secured to the plate and has a shaft 122 extending therefrom carrying gear 119 thereon whereby the counter is driven.

In operation the fluid to be metered enters at inlet 11 through passage 12 into valve chamber 6

and when inlet port 87' of the valve is in registration with supply passage 32, fluid is supplied through passage 14 to cylinder head distribution chamber 16 to force piston head 66 downwardly.

5 At the same time, the exhaust port 91 of the valve is in communication with port 33 in the body so that fluid from the cylinder head distribution chamber 25 is exhausted through passage 22 into exhaust passages 28 and 19 to the outlet 20 of the meter. In the position shown in Figure 1 the upper piston 77 has completed its exhaust stroke and the lower piston 78 has completed its intake stroke, and ports 31 and 34 are closed by the imperforate portion of valve 86. 10 Further downward movement of piston 66 brings valve port 87' in communication with port 31 and passage 13 thus supplying fluid to the cylinder head distribution chamber 17 for piston 77, while exhaust port 91 continues in communication with port 33 and uncovers port 34 to allow the exhaust of fluid from the lower end of cylinder 2 until piston 77 has reached the middle of its intake stroke. By this time valve port 87' has passed completely over port 32 and has uncovered port 31, while exhaust port 91 has completely passed over port 33 and is in registration with port 34 ready to uncover port 32. Upon further movement of piston 77 port 32 is uncovered by the exhaust port 91 and port 33 is uncovered by inlet port 87'. It is believed unnecessary to further trace the movements of the pistons and valve to completely explain the operation of the meter, as this will be readily apparent to those skilled in the art.

15 In the position shown in Figure 1 the piston 61 on the end of horizontal crank arm 48 has a considerably greater moment than the piston 60 on the vertical crank arm 48. The counterweights 49 on the crank arm, in conjunction with the counterweight 102 on the valve driving member, tend to counterbalance the moment of the pistons so that no matter in what position of the piston the meter is stopped there will be no tendency for the meter pistons to drift by their own weight and thus their resistance to movement is substantially constant. The adjusting screws 97 and 98 are provided to shift the angular relation between the valve 86' and the driving member 92 so that the timing of the valve may be adjusted and port 87' will supply fluid to the proper cylinder at exactly the proper time and exhaust port 91 will exhaust fluid from the proper cylinder at the proper time. The structure of the pistons is such that they are not massive and therefore respond readily to low flows. The meter thus readily lends itself to applications where only a relatively small pressure head is available for operating the meter.

20 What we claim as our invention and desire to secure by Letters Patent of the United States is:

60 1. A meter comprising a casing, a plurality of parallel cylinders and a distribution chamber formed in said casing, aligned bushings in the cylinder wall extending into the cylinders, a crankshaft extending through said bushings into said cylinders and having crank arms at its ends, a connecting member in each cylinder having piston heads at its ends and being provided with a transverse track to receive said crank arms, said connecting members being provided with guide tracks to receive said bushings and prevent turning of the pistons, and a valve in said distribution chamber driven by said crankshaft.

65 2. A meter comprising a casing, a plurality of parallel cylinders formed in said casing and a

distribution chamber between said cylinders, aligned bushings in said cylinder walls extending into the cylinders, a crankshaft extending through the distribution chamber and through said bushings into said cylinders and having crank arms at its ends, a connecting member in each cylinder having piston heads at its ends and being provided with a transverse track to receive said crank arms, said connecting members being provided with guide tracks to receive said bushings and prevent turning of the pistons, said members being connected to the crank arms intermediate said piston heads, and a valve in said chamber driven by said crankshaft.

3. A meter comprising a casing having a plurality of parallel cylinders and a distribution chamber between said cylinders, a crankshaft extending through said distribution chamber into said cylinders and having crank arms at its ends, a piston member in each cylinder connected to said crank arms, one wall of said distribution chamber having valve openings and an exhaust passage surrounding the crankshaft and distribution passages extending from the valve openings to the ends of the casing, a top cover for said casing having an inlet connected to said distribution chamber and distribution passages registering with those in the casing, a bottom cover for said casing having an outlet connected with said exhaust passage and distribution passages registering with corresponding ones in the casing, and a valve in said chamber driven by said crankshaft.

4. A meter comprising a casing, a plurality of parallel cylinders and a distribution chamber formed in the casing, a crankshaft extending into said cylinders and having crank arms at its ends, 5 a pair of connecting members in each cylinder each constructed of a sheet metal portion forming a skirt for guiding the piston in its movement and having turned over ends, piston heads connected to said ends, a pair of rods extending 10 through each pair of connecting members forming a slot therebetween, a pin extending through each crank arm between said rods, and a roller on each pin co-operating with said rods.
5. A meter comprising a casing, a plurality of parallel cylinders and a distribution chamber formed in the casing, aligned bushings in the cylinder walls, a crankshaft extending through said bushings and into said cylinders and having crank arms at its ends, a pair of connecting 15 members in each cylinder each constructed of a sheet metal portion forming a guiding skirt and having turned over ends, piston heads connected to said ends, a pair of rods extending through each pair of connecting members forming a slot 20 therebetween, spring detents for retaining said rods in position, pins extending through said crank arms between said rods and rollers on said pins co-operating with said rods, said connecting members providing slots in which the bushings 25 are received.

HORACE CHRISMAN.
GEORGE J. GENUNG.
